UNITED STATES PATENT OFFICE.

PATRICK J. REID, OF CHICAGO, ILLINOIS.

DESIGN FOR A WAGON-BODY.

SPECIFICATION forming part of Design No. 33,600, dated November 20, 1900.

Application filed October 15, 1900. Serial No. 33,172. Term of patent 14 years.

To all whom it may concern:

Be it known that I, PATRICK J. REID, residing at Chicago, in the county of Cook and State of Illinois, have invented and produced a new and useful Design for Wagon-Bodies, of which the following is a specification.

My invention relates to wagon-bodies and the like, but more particularly to that class or type known as "patrol-wagons."

10 The object of my invention is to produce a novel, original, and useful design for a wagon-body.

In the accompanying drawings, Figure 1 is a side elevation of my wagon-body; Fig. 2, an 15 end elevation, and Fig. 3 a front elevation thereof.

The wagon-body is rectangular in general construction, consisting of the bottom or floor A, sides B, and roof or cover C. Each side B 20 is similar and has a lower rectangular panel b and also a curved panel b' above panel b.

A pair of small windows D are provided

high up in each side B and near the top thereof to admit light into the interior of the wagon.

The roof or cover C has an extension E over 25 the driver's seat, and such extension is curved or arched, the same extending considerably in front of the driver.

The front end of the wagon, as shown in Fig. 3, is closed and is provided with the 30 barred window F. The rear end of the wagon has closed side panels G G, between which is a door H, having a window h.

The design of the wagon-body herein shown and described is not only novel and useful, 35 but is attractive and pleasing in appearance.

I claim—

The design for a wagon - body as herein shown and described.

PATRICK J. REID.
